BLUFORD W. BROCKETT, OF CLEVELAND HEIGHTS, OHIO, ASSIGNOR TO RAILWAY SERVICE AND SUPPLY CORPORATION, OF INDIANAPOLIS, INDIANA, A CORPORATION OF INDIANA

WASTE RECLAMATION APPARATUS

Application filed March 13, 1929. Serial No. 346,724.

The invention disclosed herein relates to apparatus for renovating journal box packing.

An object of the present invention is to improve and expedite the renovation of journal box packing and specifically, contemplates the feature of forming the dirty inbound packing into a mat of suitable thickness, for the passage of oil therethrough, upon an endless conveyor of the reticulated type and arranged to pass through a suitable renovator made up of a series of washing units separated from each other for maintaining oil grade and air treatment separation and each adapted to spray oil and heated air through the packing to remove from the packing the lint, dirt and other undesirable material.

Another object of the invention is to couple this type of renovator within a plant arrangement with suitable extractors for reducing the oil content of the packing to a minimum known value termed "fiber saturation", so that thereafter the waste part of the packing may be properly impregnated in another part of the plant with new oil or renovated oil which has been reclaimed or renovated and possibly after being used in the earlier steps or stages of the present packing reclamation system.

The specific invention is disclosed in the following description, drawings and claims.

In the drawings, Fig. 1 is a top plan view of the washer; Fig. 2 is a side elevation partly in section and partly broken away; Fig. 3 is a vertical section upon the line $\alpha-\alpha$ of Fig. 2; Fig. 4 shows in a schematic way a plant employing this renovating system.

In the embodiment shown in the drawings 1 represents a suitable base forming a support for a part of the entire renovating apparatus which consists of a plurality of units or casings arranged in tandem, either next to each other or in any suitable convenient arrangement. The first unit, No. 1, comprises the rectangular tank 2 of suitable height with a funnel-shape top 3 leading to a circulating stack 4, the latter receiving a motor driven fan unit 5 adapted to project air downward through a heating coil 6 arranged at the bot-

tom of the stack. The end wall of the casing 2 is provided with an upper conveyor opening 7 and a lower conveyor opening 8 adapted to receive the two stretchers of the conveyor as will appear. These openings 7 and 8 are duplicated on the opposite side of the casing 2 for the same purpose. Below and at one side of the lower openings 8 is a suitable hopper-shaped bottom 9 adapted to direct the oil passing downward into sump 10 below the base 1. Extending downward into the sump 10 is an oil pump inlet pipe 11 leading to an oil pump 12 having its discharge 13 extending upward and connected to the pipe 14 extending across unit No. 1 below the heater. This pipe has a central discharge 15 connected by a swivel joint 16 with a revolving spray pipe 17 arranged above the conveyor, as will appear. This spray pipe is driven through suitable gearing indicated at 18 by a motor 19 the speed of which may be varied to produce the proper spraying function.

Adjacent the unit No. 1 and preferably using the same common wall is the unit casing 20 similar in all respects to the casing 2 and provided at its upper end with a similar fan and heater unit. Casing 20 is also provided with a hopper bottom 21 which, at its lower central point, is connected to a drain pipe 22 controlled by a valve 23 and connected to the sump 10. At the proper time the contents of the lower portion of unit No. 2 may be discharged into the sump 10. In other words, when the oil in this unit becomes unduly contaminated it may be discharged from it into the sump thereafter there used upon the dirty packing as it enters the plant.

Connected to a low point of unit No. 2 is a pump 24 similar to the pump 12 and connected in the same manner in unit No. 2. This unit, of course, has openings in its sides similar to and in alignment with the openings 7 and 8.

Adjacent unit No. 2 is unit No. 3 comprising the casing 25 similar in all respects to the other casings except that it is provided with an inclined bottom 26, with the inclination being from right to left, as shown in the drawings, that is, toward unit No. 2 to pro-

vide a sump space at the low point. Extending into this sump space is the longer leg of a siphon 27, the shorter leg extending toward the hopper bottom of unit No. 2. This unit is also provided with an oil pump and spray pipe identical with those already employed in units No. 1 and No. 2. In like manner adjacent unit No. 3 is unit No. 4 comprising the casing 28 similar in all respects to unit 25 and provided with siphon 29 similar to siphon 27. In this instance a supply pipe 30' supplies oil to the spray pipe, said supply pipe leading from a renovated oil supply, as will appear.

15 The hopper bottoms 9 and 21 and the inclined bottoms 26 and 30 are respectively arranged in lateral casing extensions 2', 20', 25' and 28', each such casing extension communicating with its own unit casing through 20 an opening 31, Fig. 3. A suitable baffle or inclined plate 32 in each casing extends downward from the opposite wall into the extension through the opening 31 in each to a screen 33 arranged above the bottom. In 25 the case of units No. 1 and No. 2 these screens would be above the hopper bottoms 9 and 21, whereas in the case of units No. 3 and No. 4 the screens would be above the inclined bottoms 26 and 30. The siphons 27 and 29 are 30 also arranged out in these extensions.

Rotatably mounted at the left end of the plant, as shown, or ahead of unit No. 1 is a conveyor shaft 34' supporting a conveyor drum 34 which receives the bite of a reticulated conveyor 35 extending through the openings 7 and 8 in all of the renovator casings to the opposite end of the plant where it passes around another drum 36 mounted upon the shaft 37 provided with a sprocket or pulley 38 driven by a chain or belt 39 in turn driven by a motor 40. It will be understood from the foregoing that the inbound dirty packing is spread upon the upper bite of the conveyor as it moves at the proper speed into 45 the renovator.

As the dirty packing enters the first unit, it is subjected to a downward spray of oil from the spray device and a current of heated air is also driven down upon said packing 50 and through it. In this unit much of the undesirable materials, such as lint, dirt, etc., are washed out or otherwise removed. Some draining may also occur in this unit as the mat of packing passes from under the spray. 55 The main body of the removed undesirable material and the draining oil strike the baffle plate 32 and pass onto the screen 33 above one side to the hopper 9. Oil and the finer materials removed will pass through 60 the screen down into the sump 10, the dirty oil from the sump being used over again for the first stage of spraying until it becomes contaminated to the point of requiring renovation.

65 From the first unit the mat of packing

travels into the second unit where it is again subjected to a downward blast of oil and heated air and is thus washed. The oil used in this stage must be maintained in a less polluted state or in a cleaner state in order 70 to gather up additional undesirable material from the packing. It should never be permitted to reach in undesirable content that of the packing leaving the first stage. Here the dirty oil and undesirable material 75 is directed by the baffle 32 to the corresponding screen 33 which collects part of the undesirable material, the dirty oil passing out into the hopper bottom 21 from which it may be drained at the proper time by pipe 22 80 into the sump 10.

On leaving unit No. 2 the mat of packing enters unit No. 3 where it is again subjected to a blast of cleaner oil and a stream of heated air. In this case the undesirable 85 material and oil are conveyed by the corresponding baffle 32 to the screen 33 and thence to the compartment above the inclined bottom 26. As the oil builds up in this compartment it finally starts the siphon 27 and the oil in this third unit is reduced in quantity by some of it passing into the preceding compartment, that is, the compartment of unit No. 2, above the hopper bottom 21 thereof. On leaving unit No. 3 the packing 90 passes to unit No. 4 where it is again treated by a blast of still cleaner oil and heated air, the oil in this case being supplied to the spray being renovated or new oil. As the oil builds up in the bottom of unit No. 4 it starts the siphon 29 and some of the oil passes into unit No. 3, or, if this be full, both of the siphons start and dump in series into the unit No. 2 from whence the oil is drained 95 to the sump 10.

It is obvious that the number of units may be increased or decreased as desired until substantially all of the undesirable material is washed or removed from the packing and it leaves the last unit in cleaned or renovated condition and impregnated with oil ready 100 for use.

The foregoing renovator also lends itself to use in a plant installation wherein adjacent the discharge end of the conveyor there are suitable extractors 41 which may receive the saturated packing from the renovator and extract the oil therefrom to a known minimum amount or what may be termed "fiber saturation." From these extractors the extracted oil is led to a suitable storage tank 42 which is connected to and supplies the pipe 30' of the last renovator unit. This tank 42 receives its oil by means of a pipe 42' from any suitable oil renovating plant indicated at 43 and connected by a pipe 44 to the sump 10. Connected to the pipe 42' is a pipe 45 leading to a waste impregnator 46 of any preferred type.

In a plant of this type the inbound dirty 130

packing is thoroughly renovated, is extracted to a minimum point of oil extraction with the oil extracted returning for use in the last stage of the renovator and with the packing proceeding to an impregnator which is supplied with renovated oil from an oil renovator, which, in turn, is connected to the sump of the first renovator unit for reclaiming the oil contaminated in this stage and in fact throughout the entire plant.

Having described my invention, I claim:

1. Apparatus for reclaiming journal box packing, comprising a casing structure having an inlet end and an outlet end, conveyor means for supporting thereon in mat form journal box packing and for conveying the same through said casing structure from its inlet end to its outlet end, a plurality of oil discharging devices arranged in said casing structure along the path of said conveyor means, an oil storage compartment for each of said oil discharging devices and adapted to receive therefrom at least some of the oil discharged thereby, means for supplying each of said oil discharging devices with oil from its oil storage compartment, whereby said devices may be supplied with oil for discharge upon the mat of packing while it is being conveyed through said casing structure, said storage compartments from the inlet end of said casing structure toward the outlet end thereof containing oil in increasing states of cleanliness, and means for providing oil flow communication between said compartments, the communication being such that each compartment discharges directly into the preceding compartment and the discharge from at least some of said compartments being automatically effected when the oil in said compartments reaches a predetermined height.

2. Apparatus for reclaiming journal box packing, comprising a casing structure having an inlet end and an outlet end, conveyor means for supporting thereon in mat form journal box packing and for conveying the same through said casing structure from its inlet end to its outlet end, a plurality of oil discharging devices arranged in said casing structure along the path of said conveyor means, an oil storage compartment for each of said oil discharging devices and adapted to receive therefrom at least some of the oil discharged thereby, means for supplying each of said oil discharging devices with oil from its oil storage compartment, whereby said devices may be supplied with oil for discharge upon the mat of packing while it is being conveyed through said casing structure, said storage compartments from the inlet end of said casing structure toward the outlet end thereof containing oil in increasing states or conditions of cleanliness, and siphons for providing oil flow communication between said compartments, said siphons be-

ing arranged so as to cause the oil in a compartment, upon reaching a predetermined height therein, to flow into the preceding compartment, whereby each such preceding compartment receives oil in a cleaner state or condition than that which it then contains. 70

3. Apparatus for reclaiming journal box packing, comprising a casing structure having an inlet end and an outlet end, conveyor means for supporting thereon in mat form journal box packing and for conveying the same through said casing structure from its inlet end to its outlet end, a plurality of oil discharging devices arranged in said casing structure along the path of said conveyor means, an oil storage compartment for each of said oil discharging devices and adapted to receive therefrom at least some of the oil discharged thereby, means for supplying each of said oil discharging devices with oil from its oil storage compartment, whereby said devices may be supplied with oil for discharge upon the mat of packing while it is being conveyed through said casing structure, said storage compartments from the inlet end of said casing structure toward the outlet end thereof containing oil in increasing states or conditions of cleanliness, means for providing direct oil flow communication between said compartments, the communication being such that each compartment discharges directly into the preceding compartment, whereby each such preceding compartment receives oil in a cleaner state or condition than that which it then contains, and means for subjecting said mat of packing, while it is being conveyed through said casing structure, to the cleansing and agitating effects of air currents.

4. Apparatus for reclaiming journal box packing, comprising a casing structure having an inlet end and an outlet end, conveyor means for supporting thereon in mat form journal box packing and for conveying the same through said casing structure from its inlet end to its outlet end, a plurality of oil discharging devices arranged in said casing structure along the path of said conveyor means, an oil storage compartment for each of said oil discharging devices and adapted to receive therefrom at least some of the oil discharged thereby, means for supplying each of said oil discharging devices with oil from its oil storage compartment, whereby said devices may be supplied with oil for discharge upon the mat of packing while it is being conveyed through said casing structure, said storage compartments from the inlet end of said casing structure toward the outlet end thereof containing oil in increasing states or conditions of cleanliness, means for providing direct oil flow communication between said compartments, the communication being such that each compartment discharges directly into the preced- 130

ing compartment, whereby each such preceding compartment receives oil in a cleaner state or condition than that which it then contains, and a plurality of means, one adjacent and therefore cooperating with each of said oil discharging devices, for causing said mat of packing, while it is being conveyed through said casing structure, to be subjected to the cleansing and agitating effects of heated air currents.

5. Apparatus for reclaiming journal box packing, comprising a casing structure having an inlet end and an outlet end, means for supporting thereon in mat form journal box packing and for conveying the same through said casing structure from its inlet end to its outlet end, a series of oil discharging devices arranged in said casing structure along the path of said conveyor means, 20 a series of oil storage compartments, one for each of said oil discharging devices and adapted to receive therefrom at least some of the oil discharged thereby, means for supplying each of said oil discharging devices, 25 except the one nearest the outlet end of said casing structure, with oil from its oil storage compartment, means for supplying said oil discharging device nearest said casing structure outlet end with oil from a separate 30 oil supply, whereby all of said oil discharging devices may be supplied with oil for discharge upon the mat of packing, while it is being conveyed through said casing structure, said storage compartments from the inlet end of said casing structure toward the 35 outlet end thereof containing oil in increasing states or conditions of cleanliness and said separate oil supply containing oil of a still greater state or condition of cleanliness, 40 means for providing direct oil flow communication between said compartments, the communication being such that each compartment discharges directly into the preceding compartment, whereby each such preceding compartment receives oil in a cleaner state or condition than that which it then 45 contains, and an oil renovator having oil receiving communication with the first one of said oil storage compartments, namely, the 50 compartment nearest the inlet end of said casing structure, and having oil delivery communication with said separate oil supply.

6. Apparatus for reclaiming journal box packing, comprising a casing structure having an inlet end and an outlet end, a generally horizontally disposed endless conveyor for supporting in mat form on its upper stretch journal box packing and for conveying the same through said casing structure from its 60 inlet end to its outlet end, a plurality of oil discharging devices arranged in said casing structure along the path of said endless conveyor, an oil storage compartment for each of said oil discharging devices and adapted to 65 receive therefrom at least some of the oil

discharged thereby, said storage compartments having their mouths located at one side of said endless conveyor, a screen covering the mouth of each compartment, means for supplying each of said oil discharging devices with oil from its oil storage compartment, whereby said devices may be supplied with oil for discharge upon the mat of packing while it is being conveyed through said casing structure, and inclined deflector plates 75 arranged between the upper and lower stretches of said endless conveyor and leading downwardly to the mouths of said compartments, whereby oil falling upon said deflector plates will pass through the screened 80 mouths of and into said compartments.

In testimony whereof I hereby affix my signature.

BLUFORD W. BROCKETT.
